[57] CLAIM

The ornamental design for a faucet, as shown and described.

DESCRIPTION

FIG. 1 is a top, front, right side perspective view of a faucet showing my new design;

FIG. 2 is a top plan view thereof;

FIG. 3 is a front elevational view thereof;

FIG. 4 is a rear elevational view thereof;

FIG. 5 is a right side elevational view thereof, the left side being a mirror image of the right side;

FIG. 6 is a bottom plan view thereof;

FIG. 7 is a top, front, right side perspective view of a second embodiment thereof;

FIG. 8 is a top plan view of FIG. 7;

FIG. 9 is a front elevational view of FIG. 7;

FIG. 10 is a rear elevational view of FIG. 7;

FIG. 11 is a right side elevational view of FIG. 7, the left side being a mirror image of the right side; and,

FIG. 12 is a bottom plan view of FIG. 7.

The fragmentary broken line representations of holes in FIGS. 6 and 12 are for the purpose of illustration only, and form no part of the claimed design.
